United States Patent Office.

JAMES P. BLAKE, OF ROCKVILLE, MASSACHUSETTS.

Letters Patent No. 88,837, dated April 13, 1869.

IMPROVED DIE FOR MAKING AWLS.

The Schedule referred to in these Letters Patent and making part of the same.

To all whom it may concern:

Be it known that I, JAMES P. BLAKE, of Rockville, county of Norfolk, and State of Massachusetts, have invented certain Improvements in the Manufacture of Awls; and do hereby declare the following to be a full, clear, and exact description thereof, reference being had to the accompanying drawings, in which—

Figure 1 represents two dies, their faces brought together.

Figure 2 represents the face of the dies, and their peculiar construction.

The object of my invention is to manufacture awls, especially shoemakers' awls, from round steel. This has been attempted many times, but not heretofore accomplished.

By my dies awls can be made in much less time than by hand, or even by the few machines in operation.

Awls are now made by machine, but from square steel, and the process is of considerable length.

The nature of my invention consists in forming the awl between two dies, the dies so constructed as to allow of surplus metal being thrown out.

The dies are operated by a press or drop, or in any manner suitable for the purpose.

In the drawings—

A A' are dies, having recess c and recess c' of the shape of a finished awl.

On each side of recesses c and c' are wider indentations d d'; these allow of surplus metal to be detached when the dies come together, and thus the awl is cut to such perfection that but little finishing is required.

This construction of dies saves drawing down metal, and is the most expeditious and cheap means for manufacturing awls yet invented.

What I claim as my invention, and desire to secure by Letters Patent, is—

The dies A and A', constructed as shown, and for the purpose set forth.

In testimony whereof, I have signed my name to this specification in the presence of two subscribing witnesses.

Witnesses: JAMES P. BLAKE.
